[57] CLAIM

The ornamental design for a dispensing bag for fluidic uses, as shown.

DESCRIPTION

FIG. 1 is a perspective view of a dispensing bag for fluidic uses showing my new design;

FIG. 2 is an elevational view;

FIG. 3 is a view taken at right angles to the view shown in FIG. 2;

FIG. 4 is a top plan view; and

FIG. 5 is a bottom plan view.
